UNITED STATES PATENT OFFICE.

JOHN W. ENGLISH, OF HELENA, GEORGIA.

COMB ATTACHMENT.

Application filed March 21, 1922. Serial No. 545,436.

To all whom it may concern:

Be it known that I, JOHN W. ENGLISH, a citizen of the United States, residing at Helena, in the county of Telfair and State 5 of Georgia, have invented certain new and useful Improvements in a Comb Attachment, of which the following is a specification.

My invention relates to toilet articles, 10 and has particular reference to an attachment for combs.

The primary object of the invention is to provide a comb attachment in the nature of a detachable handle for the comb so 15 constructed as to be readily applied and fastened in such a manner that a direct pull may be secured on the comb when in use, ensuring a much more efficient operation thereof.

Another object of the invention is to provide a detachable comb handle constructed in such a manner that manipulation of the handle itself operates to clamp the same 20 upon the comb.

With these and such other objects in view as will be apparent from the description, my invention resides in the novel combination, construction and arrangement of parts hereinafter described and claimed, 25 and illustrated in the accompanying drawings, of which—

Figure 1 is an elevation of the attachment as applied;

Figure 2, an end elevation of same;

Figure 3, a section on line 3—3 of Figure 35 2; and

Figure 4, a section on line 4—4 of Figure 3.

In this embodiment of the invention the 40 device is shown as applied to a comb 1, and is formed in detail, of a flat clamping plate 2, carrying at one end a laterally extending stem 3, the outer end 4 of which is threaded to receive thereover a nut 5 disposed in a hexagonal socket 6 sunk in the outer end of a handle 7 mounted on the stem to rotate thereover.

On the inner end of the handle is mounted a second clamping plate 8 which is slidable over the stem and provided with a heel portion 9 adapted to rest on the inner end of the handle 7. That portion of the stem 3 which passes through the plate 8 and heel portion 9 thereof, is provided with 55 a longitudinal groove adapted to receive a rib 10 formed on the plate, whereby ro-

tation of the plate about the stem is prevented.

Clamping plates 2 and 8 extend sufficiently laterally of the handle so that they 60 may be engaged and clamped against the comb 1 over one end thereof, and these plates are of relatively long and broad configuration. In operation, the comb is inserted between the plates 2 and 8, as illustrated, and on rotation of the handle 7 nut 5 will be turned over the threaded end of the stem 3 owing to the hexagonal formation of the socket 6, whereupon the stem will be drawn within the handle to clamp 70 the plates against the comb. The length of stem 3 is such that when the handle is in attached position it will not extend beyond the outer end of the handle.

While I have illustrated and described in 75 this preferred form certain details of construction of the invention, I desire it to be understood that I do not intend to limit myself to these, but that any such may be used as will fall within the scope of the 80 invention as claimed.

I claim:

1. A device of the character described, comprising a handle member, clamping plates carried by said handle member, and 85 means in said handle member for engaging said plates in clamping relation.

2. A device of the character described, comprising a handle, a clamp disposed on one end of said handle, and means in said 90 handle for operating said clamp.

3. A comb attachment comprising a clamping plate, a stem extending therefrom, a clamping plate slidable over said stem, a handle rotatable on said stem and provided with a socket in one end, and a member carried in said socket cooperating with said stem for actuating said clamping plates. 95

4. In a comb attachment, a clamping plate, provided with a threaded stem extending therefrom, a rotatable handle disposed on said stem and provided in its outer end with a hexagonal socket, a nut disposed in said socket over said stem, a clamping plate loosely mounted on said stem between said 105 first named plate and the inner end of the handle, whereby on rotation of said handle said plates will be drawn together in clamping relation.

5. In a comb attachment, a clamping 110 plate, a threaded stem extending from one end thereof, a handle member rotatable over

said stem and provided with a hexagonal socket in its outer end, a clamping plate slidably disposed on said stem between the inner end of the handle and the first named clamping plate, means on said stem and slidale clamping plate for preventing rotation thereof, and a nut on the outer end

of said stem and carried in said handle socket whereby on rotation of said handle member the plates will be drawn together 10 in clamping relation.

In testimony whereof I affix my signature.

JOHN W. ENGLISH.
